United States Patent Office.

LUCIUS D. GOULD, OF NEWARK, NEW JERSEY.

Letters Patent No. 81,889, dated September 8, 1868.

IMPROVEMENT IN SASH-FASTENERS.

The Schedule referred to in these Letters Patent and making part of the same.

TO ALL WHOM IT MAY CONCERN:

Be it known that I, LUCIUS D. GOULD, of the city of Newark, in the county of Essex, and State of New Jersey, have invented certain Improvements in Window-Sash Supporter and Locks; and I hereby declare the following to be a full and exact description of the same, reference being herein had to the drawings that accompany this specification as part of the same.

The nature of my improvement consists in an angular bolt, sliding in the side of the eccentric, by the knob of which the eccentric is held while the sash is being moved and locked either down or up, as the case may be.

In the drawings—

Figure 1 is the sash with the supporter in position.

Figure 2 is the supporter and lock in full size as attached to the sash-stile.

Figure 3, the eccentric and the bolt.

The same letters refer to the same parts in each figure.

The eccentric, *a*, works upon the centre-pin *b*, its edge being roughened where it comes in contact with the window-frame, as at *c*. It turns on the pin, and forces the opposite sash-stile tight against the window-frame, and supports it there.

A groove, *d*, is formed in the upper part of the eccentric, *a*, in which fits and slides the bolt *e*, which, when pressed tight into the window-frame, does not slide back if the attempt is made to lift the sash, but prevents the turning back of the eccentric, so locking securely the sash.

The stem of the bolt *e*, upon which is the button or knob *f*, passes through and is movable in the curved slot *g*, in the plate *h*, covering the eccentric, *a*, and by means of the button the bolt is drawn back, the eccentric turning on its centre-pin, releasing the sash.

I do not claim broadly an eccentric as a sash-holder, nor a combined eccentric and bolt. I do not claim an eccentric combined with a bolt, cast or made fast thereto, used as a handle, nor locking a sash by moving an eccentric; but

What I do claim as my improvement, and desire to secure by Letters Patent, is—

The combination of the bolt *e* with the eccentric, *a*, when combined therewith by sliding in the eccentric in the manner and for the purpose shown.

LUCIUS D. GOULD.
